SOUND RECORDING

John G. Frayne, Pasadena, Calif., assignor to
Electrical Research Products Inc., New York,
N. Y., a corporation of Delaware

Application October 8, 1930, Serial No. 487,191
In Great Britain September 4, 1930

3 Claims. (Cl. 179—100.3)

This invention relates to sound recording and particularly to a method of recording by photographic means a wider range of sound volumes than can be recorded by known methods.

5 In any method of recording sound the range of the volumes of sound which can be satisfactorily recorded is limited by the properties of the recording medium used and the handling which the completed record receives. The least volume 10 which may be recorded is the volume which in reproduction can be satisfactorily distinguished above the noise produced by irregularities in the structure of the medium used in recording and reproducing and by the dirt, scratches, etc. which 15 collect on the record during its useful life.

The object of this invention is a system of sound recording which will produce a reduction of the volume of noise produced from a photographic sound record during the reproduction of the sound from the record. This reduction in the 20 volume of the noise produced permits smaller volumes of sound to be satisfactorily recorded and thus increases the range of volumes of sound which may be recorded. Of this invention will 25 provide a larger ratio between the present minimum volume of sound and the volume of noise produced during reproduction.

Experiments have shown that the volume of noise produced during the reproduction of a photographic sound record is approximately proportional to the average transmission of the positive sound record. The average transmission of a photographic sound record is considered to be equal to the transmission of the unmodulated 30 portions of the sound record. The transmission of a photographic medium is defined as the ratio of the light transmitted through the medium divided by the light incident on the medium and for convenience is commonly expressed as a percentage.

A feature of this invention is a method of producing a positive photographic sound record in which the average transmission of the sound record varies with the volume of the sound recorded.

45 Thus for small volumes of sound a dense record is produced and the noise produced during reproduction is a minimum.

In the reproduction of sound from a photographic sound record it has been shown that the 50 volume of the reproduced sound is proportional to the product of the average transmission of the sound record multiplied by the percentage variation in this transmission due to the modulation of the transmission in accordance with the sound. 55 In order to prevent distortion of the volume of

the sound, when the transmission of the positive sound record is reduced, the percentage modulation of this transmission must be inversely increased. For convenience in operation, the percentage modulation of the transmission is made as nearly 100% as may be practical, as this will give the smallest values of transmission of the positive sound records. Other values of modulation may be used if desired.

A photographic positive is an inverse copy of 10 the photographic negative from which the positive was printed thus if the positive sound record has a small average transmission the negative sound record must have a correspondingly large transmission. The exposure to which a photographic material is exposed is defined as proportional to the product of the intensity of the light incident on the material multiplied by the time during which the material is subjected to this light. If the complete photographic process is 20 assumed to be controlled so that no distortion is produced, then the transmission of the positive sound record will be proportional to the exposure of the negative. Accordingly, to produce a positive sound record having a small average transmission, the exposure of the negative must be correspondingly small. In accordance with this invention the time of exposure is reduced to produce a negative sound record having a large average 25 transmission.

A further feature of this invention is a method of recording sound by photographic means in which the time of exposure of the negative sound record varies directly with volume of the sound recorded and the intensity of the recording light 30 is virtually completely modulated for all volumes of sound.

In a preferred embodiment of this invention, a light valve of the type disclosed in U. S. Patent 1,638,555 granted August 9, 1927 to E. C. Wente 40 is employed. In using a light valve of this type for recording sound by the method disclosed in the above patent the intensity of the recording light does not change but the time of exposure is varied as the height of the slot defined by the 45 ribbons is varied by the movement of the ribbons. The average time of exposure will be controlled by the average spacing of the ribbons or, in other words, by the height of the slot formed when the ribbons are not displaced by a current flowing in 50 them. In accordance with the present invention a constant unidirectional current is applied to the ribbons in such direction and of such magnitude that the ribbons are nearly touching and the height of the slot defined by the ribbons is 55

small. The sound waves are detected as by a microphone and the resulting electric currents amplified in the known way and applied to the ribbons through a large condenser. A portion 5 of the amplified sound current is tapped off the output of the amplifier and fed to a rectifying device. The output of the rectifier will be a pulsating unidirectional current whose magnitude varies in accordance with the volume of the sound. 10 The output of the rectifier is supplied to the ribbons of the light valve in a direction to oppose the steady current, and cause the ribbons to move apart. The height of the slot defined by the ribbons is thus enlarged in direct proportion to the 15 volume of the sound being recorded. At the same time the ribbons are vibrated by the amplified currents from the sound detector and vary the time of exposure of the film in accordance with the modulation produced by the sound. As the 20 amplitude of the vibrations is controlled by the volume of the sound, and as the height of the slot is simultaneously controlled by rectified currents varying with the volume of the sound it will be apparent that the slot is always just large 25 enough to allow the vibration. In other words, the light passing through the valve is virtually completely modulated for all volumes of sound. Also as the slot is always opened just enough to allow for the vibrations, a loud sound cannot 30 overload the valve and cause the ribbons to clash together. In the case of a very large volume of sound, the rectified current may be larger than the steady current and cause the ribbons to be forced apart so that the height of the slot is 35 greater than the normal spacing of the ribbons with no current applied. A larger volume of sound may thus be recorded by the method of this invention than can be recorded by known methods.

40 A further feature of this invention is the provision of means whereby the ribbons of the light valve are prevented from clashing together when the valve is overloaded by a large volume of sound. It is well known that the definition of a photographic sound record is improved when the recording slot is made very small, and due to the 45 finite height of the recording and reproducing slots, there is a loss of definition and power in the reproduction of the higher frequencies of sound. Measurements have shown that for equal effects 50 on the ear much more power is required in a low frequency sound than in a high frequency sound. Thus in the present system if we consider two sounds having equal effect on the ear, one sound of low frequency and the other sound of high frequency, the low frequency sound will be of average power or volume and the ribbons of the 55 light valve will be opened to normal spacing producing a record having as good definition as the records produced by previously known methods. The high frequency sound will be of low volume and as the ribbons of the light valve will be nearly closed, the definition of the record of the high frequency sound will be better than the records produced heretofore and will partially offset the loss due to the finite height of the recording slot.

In the drawing

Fig. 1 represents in schematic form a preferred embodiment of the invention; and 70 Fig. 2 represents diagrammatically a film sound recording system.

In Fig. 1 sound waves are detected by a known type of microphone 10 and cause the current from the battery 11 to be modulated in accordance 75 with sound. The sound modulated currents in

the primary winding of transformer 12 induce similar currents in the secondary winding of the transformer. The output of transformer 12 is amplified in a known type of amplifier 13. Part of the output of the amplifier 13 is applied through a transformer 14 to the movable elements 15 of a light valve which for convenience is shown as a modification of the light valve disclosed in U. S. Patent 1,638,555 August 9, 1927 to E. C. Wente. The modulated speech currents cause the movable elements of the light valve to vibrate in accordance with the current. 10

15 In Fig. 2 the image of the filament of a suitable lamp 16 is focussed by the lens 17 on the small slot formed by the movable elements 15 in the orifice 18 pierced in the pole pieces of a permanent magnet 19. Suitable pole faces concentrate the magnetic field of the magnet 19 to form a uniform magnetic field in which the movable elements 15 are immersed. An electric current flowing in the movable elements 15 will cause the elements to be displaced by the reaction of the magnetic fields due to the current and the magnet. The image of the slot is focussed by the lenses 20 and 21 on a photographic film 22 moving at uniform speed past the point of exposure. An aperture plate 23 holds the film smooth at the point of exposure and prevents diffused light from fogging the record. 25

30 In Fig. 1 a portion of the sound modulated currents from the amplifier 13 is applied through a tapped transformer 24 to the grid of a vacuum tube 25. The bias applied to the grid of the vacuum tube 25 may be varied by means of the potentiometer 26. The sound modulated input 35 to the grid of the vacuum tube 25 may be varied by means of the taps brought out from the secondary of the transformer 24. The plate current of the vacuum tube may thus be adjusted to any convenient value and the sound modulated input adjusted to obtain the highest coefficient 40 of detection. Plate current is supplied to the vacuum tube 25 from a battery 27 through the coupling resistances 28 and 29 which may conveniently be in the form of a tapped resistance. 45 The combined resistances 28 and 29 are of suitable value to assist in producing complete detector action in the vacuum tube 25.

50 The detected currents in the output of the vacuum tube 25 produce a pulsating voltage across the resistance 29 which is applied to the grid-filament circuit of a vacuum tube 42. A steady bias is applied to the grid of the vacuum tube 42 by a battery 32 and the value of this bias may be adjusted by the potentiometer 31 shunted across the 55 battery 32.

60 The grid of vacuum tube 42 is connected to the junction of the resistances 28 and 29 and the wire 43 from the biasing potentiometer 31 is connected to the plate of the vacuum tube 25. The steady component of the plate current of the vacuum tube 25 flowing in the resistance 29 will produce a voltage drop across the resistance 29 which reduces the bias on the grid of the vacuum tube 42. Thus when sound modulated currents 65 are detected by the vacuum tube 25, the bias on the grid of vacuum tube 42 will be reduced and the plate current of vacuum tube 42 will increase. A choke coil 50 in the output circuit of the vacuum tube 25 cooperates with a condenser 51 connected across the output circuit to form a smoothing circuit. The smoothing circuit causes the voltage variations developed across the resistance 29 to follow the envelope of the amplitude variations of the sound modulated currents 70 75

and not the instantaneous variations in amplitude.

Current from a battery 44 is applied through a variable resistance 45 to the movable elements 15 of the light valve and cause the movable elements 15 to reduce the slot to a small value which may be adjusted by means of the resistance 45. The plate current of the vacuum tube 42 flows from the battery 46 through the vacuum tube 42, wires 47 and 48, and the movable elements 15 to the battery 46. This current will flow in a direction to oppose the current from the battery 44 flowing in the movable elements 15 and to tend to cause the movable elements 15 to open the slit. A high resistance 49 permits the plate current flowing through the movable elements to be adjusted.

The operation of the circuit shown in Fig. 1 is as follows: When no sound modulated current is applied to the circuit, the bias applied to the grid of the vacuum tube 42 is adjusted so that the plate current flowing in the movable elements 15 is very small and the current from the battery 44 flowing in the movable elements 15 is adjusted so that the slot defined by the movable elements 15 is small. When sound modulated current is detected by the vacuum tube 25, the voltage drop across the resistance 29 will increase and reduce the bias applied to the grid of the vacuum tube 42. The plate current from the vacuum tube 42 flowing in the movable elements 15 will increase and partially overcome the effect of the current from the battery 44 and permit the movable elements 15 to move apart and open the slot. Simultaneously the sound modulated currents from the transformer 14 cause the movable elements 15 to vibrate. By suitably adjusting the input to the vacuum tube 25 the slot may be opened just enough to allow the full amplitude of the vibration of the movable elements 15 and substantially complete modulation of the light reaching the film will be attained for all volumes of sound. A condenser 52 connected across the output of the vacuum tube 42 causes the vacuum tube 42 to respond more rapidly to changes in amplitude of the sound modulated currents so that the slot in the light valve is quickly increased in height when a sudden loud sound is detected by the microphone 10. When the volume of sound is sufficiently large the plate current from vacuum tube 42 flowing in the movable elements 15 will equal the current from battery 44 flowing in the movable elements 15 and the height of the slot will be determined by the mechanical adjustment given to the movable elements 15. This is the maximum volume which may be recorded by known systems of light valve recording. A further increase in the volume of sound will cause the plate current from the vacuum tube 42 flowing in the movable elements 15 to become greater than the current from battery 44 flowing in the movable elements 15 and to force the movable elements 15 apart so that the mean spacing of the elements is greater than the spacing due to the mechanical adjustment. The light valve can thus record a volume of sound which in known types of light valve would ordinarily overload the valve and cause the movable elements to clash together.

While the invention has been applied to a specific form of light valve it will be obvious to those skilled in the art that the invention is not limited to the specific type of light valve disclosed.

What is claimed is:

1. In a system for recording modulated currents on a moving film, in combination, a source of light, a light valve actuated by modulated currents to vary the light from said source incident on the film, a detector energized by modulated currents, a thermionic amplifier having its control electrode connected to the output of said detector and having the light valve connected in serial relation in its output circuit, a source of constant current in series with a variable resistance connected in shunt with the light valve to oppose the output current flowing in said light valve, and a second variable resistance in parallel relation with said source of current whereby the anode current of said amplifier is substantially unchanged by an adjustment of the current flowing in the light valve. 5 10 15

2. In a system for recording modulated currents on a moving film, in combination, a source of light, a light valve actuated by modulated currents to vary the light from said source incident on the film, a detector energized by modulated currents, a thermionic amplifier comprising a cathode, an anode and a control electrode, means 20 for applying a voltage varying with the output of said detector between the cathode and the control electrode of said amplifier, a source of current in serial relation with said light valve connected between the anode and the cathode of 25 said amplifier, a second source of current in serial relation with a variable resistance connected in shunt with said light valve to oppose the current from said first source flowing in the light valve, and a second variable resistance in shunt with 30 said second source of current, said second resistance being operated simultaneously with said first resistance whereby the anode current of 35 said amplifier is substantially unchanged by an adjustment of the current flowing in the light 40 valve. 45

3. In a system for recording modulated currents on a light-sensitive medium, in combination, means for directing a beam of light on said medium, a light valve having movable elements 45 mechanically adjusted to define an image of said beam of normal height in the direction of motion of said medium, a circuit for supplying modulated currents to vibrate said movable elements, means for applying a constant current to 50 said elements to decrease the height of said normal image, a detector energized by said modulated currents, a resistor in the output circuit of said detector, a thermionic amplifier having a cathode, an anode, and a control electrode, 55 a source of current in serial relation with the movable elements of said light valve connected between said cathode and said anode so as to oppose the constant current in said elements, a source of biasing potential in serial relation with 60 said resistor connected between said cathode and said control electrode and adjusted so that in the absence of modulated currents the anode current of said amplifier is substantially zero, said resistor being so connected that the potential 65 difference across said resistor tends to reduce said biasing potential whereby in the presence of modulated currents, the anode current of said amplifier reduces the effect of the constant current in said elements, and at times causes said 70 elements to increase said image to a height greater than the height due to the mechanical adjustment. 75
